BAG HOLDERS

Harold K. Fox, Minneapolis, Minn., assignor to Bemis Bro. Bag Company, Minneapolis, Minn., a corporation of Missouri

Application November 19, 1951, Serial No. 257,164

5 Claims. (Cl. 248—101)

This invention relates to new and useful improvements in bag holders and more particularly to such an apparatus having means embodied therein for preventing spouting of the material from the bag during the filling operation.

It is now common to package powdered milk and other comminuted products in large moisture proof bags, the walls of which are made imperforate or non-porous, as is well known, to prevent the penetration of moisture through the bag walls into the contents thereof. Powdered milk is highly susceptible to moisture and rapidly deteriorates when subjected thereto, and it is therefore customary to package such materials in large waterproof bags preferably having multi-ply walls to provide adequate strength and flexibility to resist rough handling when the filled bags are transported from one place to another.

When introducing powdered milk or other analogous materials into non-porous bags, there is a tendency for the material to spout from the bag mouth, which is highly objectionable, and an object of the present invention is to provide a bag holder having means embodied therein for completely overcoming this difficulty, whereby such bags may be expeditiously filled without danger of the material spouting into the air around the packing tube during the filling operation, as is now a common occurrence with various types of conventional bag holders.

A further object of the invention is to provide a bag holder for supporting the open top or mouth of a bag of a large flexible walled bag in filling position upon a conventional packer tube, whereby such bags may readily and quickly be filled without danger of the material spouting from the open mouth thereof.

A further object is to provide a bag holder having means for supporting it in operative relation to the packer tube and comprising a pair of clamping jaws mounted for swinging movement in a horizontal plane and interconnected for simultaneous movement in opposite directions, and said jaws having means at their outer ends for securing them in bag holding position during the filling operation.

A further object is to provide a bag holder attachment for a conventional packer tube comprising a hollow member of spheroidal cross-section having means for securing it to the packer tube with its long dimension disposed in the median plane of the bag body, when an empty bag is secured thereto by the clamping jaws, and the opposed side walls of said hollow member co-acting with said jaws to grip the intermediate portions of the bag top walls when the jaws are operatively engaged with the bag top.

A further object is to provide a bag holder comprising a hollow member of spheroidal cross-section having means for securing it to the packer tube in axial alignment therewith, and a pair of pivoted clamping jaws being mounted to clampingly engage the opposed side walls of said member with a "wiping" action, when said

2

jaws are brought together to secure the opposed walls of a bag top thereto, and a porous hood sealing the open top end of said hollow member to prevent spouting of the material therefrom during the filling operation, the porous walls of said hood permitting air to escape therethrough to the atmosphere and also prevent a back pressure from developing within the body of the bag during the introduction of the material thereto.

Other objects of the invention reside in the means provided for supporting the hollow spheroidal member on the packer tube; in the means provided for engaging and supporting the rear end of the bag top when said top is fitted over the spheroidal member, thereby to retain the bag top in proper position on the packer tube before it is secured thereto by the clamping jaws; in the flexible facing provided on the clamping jaws for engaging the bag top walls whereby said walls are firmly pressed into clamping engagement with the opposed side walls of the spheroidal member in substantially leaktight relation, and whereby the bag top cannot accidentally become detached from the packer tube during the filling operation; in the cam means provided for retaining the jaws in clamping engagement with the bag top fitted over the packer tube, including a latch member pivoted to the outer end of one of the clamping jaws and an adjustable roller secured to the other of said jaws; in the adjustable mounting of the depending finger for engaging the rear end of each bag top to accurately locate the bag top vertically relative to the jaws to prevent damage to the adhesive-coated area, and more particularly to the strip of sealing tape which is normally attached to one of the side walls of the bag top during the manufacture thereof; and also whereby each bag top will be properly centered on the packer tube by said jaws; in the novel construction of the jaws and said spheroidal member whereby all wrinkles and any rough surfaces present in the bag top walls prior to securing the bag top in position on the packer tube to receive a charge, are positively removed therefrom when the bag top walls are pressed into sealing engagement with the opposed walls of the spheroidal member, thereby preventing any of the material delivered into the bag from contacting the adhesive coated area thereof or the attached sealing tape.

These and other objects of the invention and the means for their attainment will be more apparent from the following description taken in connection with the accompanying drawings.

In the accompanying drawings there has been disclosed a structure designed to carry out the various objects of the invention, but it is to be understood that the invention is not confined to the exact features shown, as various changes may be made within the scope of the claims which follow.

In the drawings:

Figure 1 is a sectional elevation of a conventional packer tube showing the invention attached thereto;

Figure 2 is a sectional plan view on the line 2—2 of Figure 1, showing a bag top secured in position on the packer tube to receive a charge;

Figure 3 is a sectional plan view substantially on the line 3—3 of Figure 1, the full lines showing the jaws in wide open positions, and the dotted lines indicating the positions of the jaws when initially engaging the bag top walls;

Figure 4 is a sectional plan view on the line 4—4 of Figure 1, showing the clamping jaws in operative engagement with a bag top;

Figure 5 is an enlarged detail sectional view on the line 5—5 of Figure 1;

Figure 6 is a detail sectional view on the line 6—6 of Figure 7, showing the adjustably mounted anti-friction roller or sleeve mounted on the outer end of one of the

clamping jaws for engaging the latch member carried by the other of said jaws;

Figure 7 is an enlarged detail sectional view on the line 7-7 of Figure 6;

Figure 8 is a view similar to Figure 7, but showing a bag top positioned between the jaws; and

Figure 9 is a view showing the upper end of the spheroidal member closed to the atmosphere to provide a closed chamber, and one end of a suction tube being in communication therewith.

In the selected embodiment of the invention herein disclosed, there is illustrated in Figure 1, for purposes of disclosure, a conventional packer tube 2 having its upper end in communication with a hopper 3. The novel bag holder attachment herein disclosed is shown comprising a hollow member, generally designated by the numeral 4, which is spheroidal in cross section, as illustrated in Figures 2, 3 and 4, and is secured to the packer tube 2 by a horizontally disposed web 5 having its opposed side edges shaped to coincide with the curvature of the opposed side walls 6 and 7 of the member 4, as best illustrated in Figure 4. The opposed edges of the web 5 are fixedly secured to the inner surfaces of the walls 6 and 7 by such means as welding, and the web has an enlarged central aperture therein for receiving the packer tube 2 to which it may also be welded.

A horizontally disposed plate 8 is shown having one end suitably secured to a U-shaped bracket 9 by such means as welding. Bracket 9 is secured to a horizontal member 11 having its end portions secured to a supporting structure including a pair of spaced uprights 12 and 13, shown in Figures 1, 3, and 4. The bracket 9 may be secured to the member 11 by suitable bolts 14, indicated in dotted lines in Figure 1. The upper ends of the uprights 12 and 13 may be secured to an upper supporting member 15 having its forwardly extending end portion 16 secured to the packer tube 2 by such means as clamping bolts 17.

A pair of clamping jaws 18 and 19 are shown mounted for pivotal movement on vertically disposed pivots 21 and 22, respectively, having their upper ends supported in plate 8 and fixed thereto by welding, as indicated at 23 in Figure 5. Arms 18 and 19 are preferably shaped as illustrated in Figure 3, and have their inner faces lined with a suitable resilient facing 24 such as sponge rubber, for frictionally engaging and clamping the opposed side walls 25 and 26 of the bag top against the opposed segmental side walls 6 and 7, respectively, of the hollow member 4, as will be understood by reference to Figure 4. It will be noted by reference to Figures 2, 3 and 4, that the long dimension of the hollow member 4 is disposed in the median plane of the bag top, whereby the bag top engaging surfaces of the clamping jaws will engage the bag top walls the full length thereof, when the jaws are in bag top clamping positions, as shown in Figure 4.

The spheroidal configuration of the hollow member 4 constitutes an important feature of the present invention in that its opposed convex side walls 6 and 7 cooperate with the concave bag top engaging faces of the jaws 18 and 19 to impart what might well be termed, a "wiping" action of the jaws with the bag walls when the jaws are swung into clamping engagement therewith, as shown in Figure 4. In Figure 3 it will be noted that as the jaws are swung inwardly into engagement with the bag top walls, the portions A-A theretof initially engage the bag walls, as indicated by the dotted lines in Figure 3.

As the jaws continue inwardly from the dotted line positions there shown, the portions A-A of the arms swing inwardly and rearwardly, as indicated by the broken lines a-a in Figure 3, whereby they engage the bag walls with a "wiping" action as they are moved into clamping engagement therewith, as shown in Figure 2. It is to be understood that during the movement of

the jaws into clamping engagement with the bag top walls, the forward edge of the bag top is held in the position shown in Figure 3 by the operator who grasps the bag top at point B below the jaws 18 and 19, and pulls it forwardly, as indicated by the arrow in Figure 3. Such action of the jaws on the bag walls is highly important in that it smooths out the deckled edge of the bag top and any wrinkles or roughness which may be present therein when the bag top is initially fitted over the member 4.

To secure the jaws in bag top clamping positions, as shown in Figure 4, a latch member 27 is pivoted to arm 18 by a pivot pin 28. The latch member is provided at one end with an operating handle 29 and at its opposite end with a cam face 31 adapted to engage an anti-friction roller or sleeve 32 rotatably mounted upon a fixed eccentric 33, adjustably secured in the end of arm 19 by a lock screw or bolt 34, best illustrated in Figure 7.

To facilitate adjustment of the eccentric 33 relative to arm 19, the eccentric may be secured to the bolt 34 so that when the nut 35 on the bottom end of bolt 34 is loosened, the cam may be rotatively adjusted in the arm 19 by rotating the head of bolt 34, as will readily be understood. The eccentric is locked in adjusted position by the nut 35. The cam face 31 terminates at its inner end in a recess 36 adapted to receive the roller 32 and retain the latch 27 in locking engagement with roller 32, as will be understood by reference to Figure 6.

To facilitate swinging the jaws into clamping engagement with the bag top, the jaws are provided with inter-engaging gear segments 37 and 38, best shown in Figure 3, whereby the arms operate simultaneously in opposite directions and may readily be operated with one hand, as will be understood. The gear segments 37 and 38 are shown secured to the lower end of elongated hubs 39 and 41 bored to receive the pivot pins 21 and 22, respectively, as best illustrated in Figure 5. The gear segments are secured to the upper portions of the jaws 18 and 19 by welding or other suitable means, whereby the elongated hubs 39 and 41 provide, in effect, an integral part of their respective jaws 18 and 19.

In the packaging of dried milk and other materials of a similar character, in large multiply bags, it is customary to seal the open tops thereof with a suitable sealing tape which is folded over the flattened bag top walls and suitably bonded thereto. In such bags it is also customary to attach the strip of sealing tape, indicated at C in Figure 8, to one of the walls of the flattened bag top during the manufacture of the empty bags, whereby one-half of the tape projects above the bag top and is provided with a suitable adhesive which is non-tacky when in its normal state. A similar adhesive may also be applied to the upper marginal edge portion of the other bag top wall adapted to be engaged by the projecting half of the tape, when subsequently folded over the bag top and into engagement with the other bag top wall to be bonded thereto by the application of heat and pressure.

By reference to Figure 8 it will be noted that the clamping jaws 18 and 19 engage the bag top at a point below the lower edge of the sealing tape C, whereby the adhesive coated portion of the sealing tape and also the adhesive coated upper marginal edge of the opposite bag top wall are disposed above the jaws 18 and 19. When the sealing tape is thus applied to the bag top before the filling operation, it is extremely important that the adhesive coated surfaces of the tape and bag top wall be kept free from foreign matter, as will be understood.

Means is provided for definitely vertically locating the bag top on the filling tube to assure the operator that the adhesive coated portion of the bag top and the half attached sealing tape C are located above the jaws 18 and 19, when the latter are engaged with the bag top as shown in Figure 8. To thus position and center

the bag top on the filling tube, a depending plate 42, is shown adjustably mounted on the leg 43 of an angle iron bracket 44 by suitable bolts 45, received in a horizontal slot 46 provided in the leg 43, as shown in Figure 1. Angle bracket 44 is secured to the plate member 8 by suitable bolts 47. By thus mounting the finger 42, it may readily be adjusted in fore-and-aft directions relative to the packing tube 2 to adapt the holder for bag tops of different sizes. Plate 42 has a portion 40 adapted to enter the bag mouth, and a shoulder 50, which serves as a limit stop for the upward movement of the bag top on the filling tube, as will be understood by reference to Figure 1.

In the operation of the novel bag holder herein disclosed the operator grasps an empty bag top and spreads the walls thereof and slips them over the lower end portion of the hollow spheroidal member 4 with the rear end of the bag top engaging the abutment shoulder 50 on the plate 42, as illustrated in Figure 1. The operator then grasps the opposite or forward end 48 of the bag top with one hand, and tensions the bag top walls by exerting a pull thereon in the direction indicated by the arrow in Figure 3, thereby to firmly retain the rear end of the bag top in engagement with the finger 40 of the plate 42. He then grasps one of the jaws with his other hand and swings it in a direction towards the bag top, whereupon both jaws are simultaneously swung into clamping engagement with the bag top walls, as shown in Figure 4, after which the latch 37 is actuated to secure the clamping jaws in their operative positions.

When the bag top is thus secured to the packing tube, the entire mouth of the bag is completely closed and sealed so that material delivered into the bag from the packing tube cannot spout from the bag mouth. This will be readily understood by reference to Figure 4, wherein it will be noted that the end portions of the bag top which extend beyond the ends of the hollow member 4 are pressed into flatwise relation by the resilient facings 24 of the clamping jaws, as indicated at 49 in Figures 2 and 4. At the same time the arcuately formed intermediate portions of the clamping jaws similarly clamp the bag top walls against the side walls 6 and 7 of the member 4 with a "wiping" action to smooth out the deckle edges of the bag top walls, and any other rough spots appearing thereon.

To prevent the material from spouting from the upper end of member 4, a hood 51, preferably of a porous textile fabric, has its lower end secured to the upper end of the member 4 and its upper end to the packing tube by suitable means, such as a clamping band 52. The web 5 which connects the inner surfaces of the walls 6 and 7 of member 4 with the periphery of the packing tube 2, is formed to provide air circulating passages 53 at the ends of member 4, whereby air confined within the bag body and which may be entrained with the material during the filling operation, may pass upwardly from the bag through the air passages 53 and through the pores in the walls of the hood 51 to the atmosphere.

The porosity of the walls of the hood 51 is such that finely comminuted material or dust cannot escape through the pores thereof, but the air trapped within the bag may freely escape therethrough. Thus, the operation of filling bags on a packing equipped with the novel bag holder herein disclosed, may be accomplished in a dust-free atmosphere. When the bag has received its full charge it may be delivered onto a suitable conveyor (not shown) positioned beneath the packing tube for transportation to an adjacent station or apparatus for closing and sealing the bag top by folding the sealing tape C over the flattened bag top walls and adhering it thereto. In the accompanying drawings, the jaws 18 and 19 are shown mounted for manual operation. It is to be understood, however, that if desired, means may be provided whereby said jaws may be operated by a foot pedal or by power means, without departing from the scope of the invention.

In Figure 9 there is illustrated a slightly modified construction wherein the upper end of the member is sealed by a top plate or wall 54 having one end of a suction tube 55 attached thereto which communicates with the interior of member 4. In the form here shown the suction through the tube 55 is so controlled that only the finely pulverized material or dust is extracted from the member 4 and the upper end of the bag being filled during the filling operation.

The foregoing detailed description has been given for clearness of understanding only, and no unnecessary limitations should be understood therefrom, but the appended claims should be construed as broadly as permissible in view of the prior art.

I claim as my invention:

1. In combination with a packing tube having its upper end in communication with a hopper for supplying material thereto, a hollow member of spheroidal cross-section fitted over and secured to the packing tube with its spheroidal walls spaced outwardly from the walls of the packing tube, a pair of clamping jaws mounted for pivotal movement in a horizontal plane and interconnected for simultaneous operation in opposite directions, said jaws having concave wall portions cooperating with the spheroidal walls of said member to secure a bag top thereto to receive a charge from the packing tube, and a shouldered element positioned to be engaged by each bag top to vertically locate the bag top on said hollow member to assure accurate engagement of the bag top walls by said clamping jaws when said jaws are swung into clamping engagement with the walls of a bag top.

2. In combination with a packing tube having its upper end in communication with a hopper for supplying material thereto, a hollow member of spheroidal cross-section fitted over and secured to the packing tube with its spheroidal walls spaced outwardly from the walls of the packing tube, a support for said tube and member, a pair of clamping jaws mounted for pivotal movement in a horizontal plane and interconnected for simultaneous operation in opposite directions, said jaws having concave bag top engaging wall portions adapted to cooperate with the opposed walls of said member to secure a bag top to the packing tube in filling relation thereto, an element secured to and depending from said support and engageable with the rear end portion of each bag top for supporting vertically locating and centering each bag top on said hollow member prior to being engaged by the clamping jaws, and said jaws engaging the bag top walls with a "wiping" action, thereby to remove all wrinkles from the bag top walls during the operation of securing the bag top to said member.

3. A bag holder for supporting large flexible walled bags to be filled with powdered dry milk, a packing tube, a hollow member of spheroidal cross-section fitted over and secured to the lower end of the packing tube with its spheroidal walls spaced from the walls of the packing tube, a support for the packing tube and said hollow member, a pair of clamping jaws mounted for pivotal movement on said support and swingable about vertically disposed axes located at opposite sides of the median plane of said hollow member, means interconnecting said jaws for simultaneous operation in opposite directions, the curvatures of the inner concave bag-engaging faces of said jaws corresponding substantially to the curvatures of the outer convex surfaces of the opposed side walls of said hollow member, whereby the opposed walls of a bag top may be firmly gripped between said jaws and the walls of said hollow member, and a bag top engaging element secured to and depending from said support and having a portion adapted to be received in an open bag top, whereby when one end of a bag top is fitted over said hollow member and a pull is exerted over said hollow member and a pull is exerted on the opposite end of the bag top, said jaws may be swung into clamping engagement with the bag top walls to secure the bag top to said hollow member in

leaktight relation and with the assurance the bag top walls will be free from wrinkles.

4. A bag holder, according to claim 3, wherein the opposite ends of said jaws are flat and firmly press the opposed end portions of the walls of the bag top into flatwise relation against one another, when the bag top is secured to the hollow member by manipulation of said jaws.

5. A bag holder for supporting large flexible walled flat bags to be filled with powdered dry milk, or the like, a packer tube, a hollow member of spheroidal cross-section fitted over and secured to the lower end of the packer tube with its long dimension extending from front to rear of the apparatus, a support for the packer tube and said hollow member, including a horizontal plate, a pair of bag top clamping jaws mounted for pivotal movement on, 15 said support and swingable about vertically disposed axes located at opposite sides of the median plane of said hollow member, means interconnecting said jaws for simultaneous operation in opposite directions, the inner bag-engaging faces of said jaws being concave and corresponding substantially to the outer convex surfaces of the opposed walls of said hollow member, and a bag top engaging element secured to and depending from said horizontal plate and having a portion adapted to be received 20 in the mouth of a bag fitted over said hollow member,

5
10
15
20
25

said element supporting the rear portion of the bag top and limiting its upward movement relative to said jaws, whereby the jaws will engage the bag top at a location spaced downwardly from the upper marginal edges of the bag top walls, when the operator exerts a pull on the forward portion of the bag top to maintain the bag top walls taut between said depending element and the operator's hand, and whereby when said jaws are swung into clamping engagement with the bag top walls, they will engage the bag top walls with a wiping action, thereby to remove all wrinkles from the bag top walls during the operation of securing the bag to said hollow member for filling.
